US00D856984S

(12) **United States Design Patent** (10) Patent No.: **US D856,984 S**
(45) Date of Patent: **** Aug. 20, 2019**

(54) **COMPACT MULTI-BAND ANTENNA**

(71) Applicant: **Redpine Signals, Inc.**, San Jose, CA (US)

(72) Inventors: **Deepu Vasudevan Nair**, Thiruvananthapuram (IN); **Varun Ramchandani**, Kota (IN); **Partha Sarathy Murali**, San Jose, CA (US); **Suresh Kumar Vagvala**, Hyderabad (IN)

(73) Assignee: **Redpine Signals, Inc.**, San Jose, CA (US)

(**) Term: **15 Years**

(21) Appl. No.: **29/616,310**

(22) Filed: **Sep. 5, 2017**

(57) **CLAIM**

The ornamental design for a compact multi-band antenna, as shown and described.

DESCRIPTION

FIG. 1 is a top plan view of a first embodiment of a compact multi-band antenna showing the new design; and, FIG. 2 is a top plan view of a second embodiment thereof. The black areas comprise the entirety of the claimed design. All elements of the claimed design are flat and coplanar. The broken line showing of a circuit board forms no part of the claimed design.

1 Claim, 1 Drawing Sheet
